UNITED STATES PATENT OFFICE.

JOHN R. FORTUNE, OF DETROIT, MICHIGAN, ASSIGNOR TO MURPHY IRON WORKS, OF DETROIT, MICHIGAN, A CORPORATION OF MICHIGAN.

FURNACE-RETORT.

1,180,287.

Specification of Letters Patent. Patented Apr. 25, 1916.

Application filed November 23, 1914. Serial No. 873,572.

To all whom it may concern:

Be it known that I, JOHN R. FORTUNE, a citizen of the United States, residing at Detroit, in the county of Wayne and State of Michigan, have invented certain new and useful Improvements in Furnace-Retorts, of which the following is a specification.

Underfeed furnace constructions in which the fuel retort has a reciprocatory bottom or floor for feeding the fuel,—that is, pushing it inwardly and upwardly—have heretofore been proposed; but one of the disadvantages of this style of stoker structures has been the lack of proper joints between the sliding 15 part of the retort and the coöperating stationary portions.

The prime object of the present invention is the improvement of such joints so as to effectively prevent the coal from interfering 20 with the correct functioning of the structural members.

In the preferred embodiment of the invention, not only the floor or bottom wall of the retort is reciprocable, but also the lower 25 or adjacent portions of the retort side-walls are made to slide with the floor, and preferably form an integral part thereof. The joints therefore are part way up the sides of the retort and are between the stationary 30 and movable portions of the side walls. It has been found that by making these joints inclined,—that is, converging downwardly toward the retort—the fuel is effectually prevented from entering them, and cannot 35 therefore clog the joints and interrupt or interfere with the reciprocation of the parts. Owing to the downward inclination or sloping of the spaces or joints between the sliding and stationary parts, any coal in the 40 retort at the joint which might be pushed slightly into the joint is soon discharged, as the disposition or inclination of the joint makes it self-cleaning and facilitates the expulsion of anything which may enter.

In order that those skilled in this art may have a full understanding of the invention, I have illustrated the preferred embodiment of the same in the accompanying drawing forming a part of this specification, and 50 throughout the views of which like reference characters refer to the same parts.

In this drawing, Figure 1 is a vertical cross section through the retort and illustrates portions of the side grate bars; and 55 Fig. 2 is a fragmentary, vertical, longitudi-

nal section through the center of the retort, on line 2—2 of Fig. 1.

In this particular embodiment of the invention, the structure is supplied with two side supports 10 and 11, bolted together near 60 the bottom at 12, and adapted to support the fuel retort and the upper ends of the adjacent grate bars. On its inner side, each of these supports is equipped with a ledge or shelf 13, 13, on which the sliding part of the 65 retort is supported and adapted to reciprocate. The bottom wall 14 of the retort is provided on its under face at its two edges with depending stiffening ribs or flanges 15, 15, and the lower portions 16, 16 of the side 70 walls of the retort project upwardly from the margins of the floor or bottom wall 14, and are preferably, though not necessarily, cast integral therewith. At their upper edges, these walls 16, 16 are provided with 75 outwardly projecting ribs 17, 17, which have flat or plane bottom surfaces resting and riding on the top faces of the supporting ribs 13, 13. The top surfaces of these ribs are inclined at 18, 18, as illustrated. That is 80 to say, they converge downwardly toward the center of the retort. The stationary or upper portions 19, 19 of the retort side-walls are secured by means of bolts 20, 20 to the side supports 10 and 11, and their lower 85 faces are inclined or beveled at 21, 21, to correspond to or match the inclination of the surfaces 18, 18, so that these coacting surfaces form downwardly converging joints. The grate bars 22, 22 incline downwardly 90 from opposite sides of the retort, as is clearly shown.

In order to carry the coal rearwardly of the retort and also force it upwardly so as to overflow onto the opposite grate sections, the bottom wall or floor 14 of the receptacle has one or more fuel pushers 23, which during the rearward reciprocation of the retort floor, push the coal rearwardly and upwardly, but which, owing to their shape or 95 form, ride under the coal readily during the forward sliding of the retort floor.

As has been indicated above, the principal feature of this invention is the character of the joints 18—21, which are so constructed as to prevent the entrance of coal thereto and to facilitate its discharge if any of the fuel should find access to the joints. That is to say, the joints are inclined, and consequently tend, both by their disposi- 100 105 110

tion and inclination and the relative reciprocation of the parts, to quickly dislodge any fuel or other matter which might find access to them. I have found that the employment of these joints prevents the coal from in any way interfering with the proper reciprocation of the sliding bottom wall and the portions of the side walls carried thereby.

10 While I have herein indicated only one style of structure embodying this invention, it is to be understood that the invention is not limited and restricted to the precise and exact details of construction set forth, because these may be modified within reasonable limits without departing from the heart and substance of the invention and without sacrificing any of the substantial benefits and advantages.

15 20 In this application I have illustrated and described one desirable style of structure, but it should be remembered that this inclined joint feature need not necessarily be located between stationary and movable parts of the retort side-walls but may in some instances be as advantageously employed between the retort bottom-wall or floor on which the fuel rests and the side-walls.

25 30 I claim:

1. In an underfeed-furnace stoker-construction, a fuel retort having its floor and the lower portions of its side walls longitudinally reciprocable, the joints between the

upper edges of the sliding side-wall portions and the lower edges of the stationary side-wall portions having their outer parts higher than their inner parts, substantially as described.

2. In an underfeed-furnace stoker-construction, a fuel retort having its floor and the lower portions of its side walls longitudinally reciprocable, the joints between the upper edges of the sliding side-wall portions and the lower edges of the stationary side-wall portions being downwardly converging, substantially as described.

3. In an underfeed-furnace stoker-construction, a fuel retort having a stationary upper part and a reciprocatory lower part, the joint between the two parts being downwardly inclined toward the interior of the retort, substantially as described.

4. In an underfeed-furnace stoker-construction, a fuel retort having a stationary side-wall and a reciprocatory part on which the fuel is adapted to rest, the joint between said side-wall and reciprocatory part being downwardly inclined toward the interior of the retort, substantially as described.

In testimony whereof I have hereunto signed my name in the presence of two subscribing witnesses.

JOHN R. FORTUNE.
